UNITED STATES PATENT OFFICE.

BERNARD KERN, OF SANDUSKY, OHIO.

STREET-SWEEPING MACHINE.

1,288,028.

Specification of Letters Patent. Patented Dec. 17, 1918.

Application filed November 19, 1914. Serial No. 873,009.

To all whom it may concern:

Be it known that I, BERNARD KERN, a citizen of the United States, residing at Sandusky, in the county of Erie and State of Ohio, have invented certain new and useful Improvements in Street-Sweeping Machines, of which the following is a specification, reference being had therein to the accompanying drawing.

10 This invention relates to improvements in street sweeping machines of that type wherein brushing means are utilized to loosen the refuse from a street surface, in the zone of influence of a volume of air for lifting and 15 conveying such refuse to a suitable point of deposit, as for example, to a separating system, or dump cart, not necessary to be referred to in detail herein.

An object of the present invention is to 20 provide a suitable conduit, in conjunction with an exhaust fan, said conduit being provided with a suitable inlet nozzle or mouthpiece, the latter being of an elongated flexible nature enabling the sections thereof to 25 adjust themselves in keeping with the road surface over which the machine travels; and more specifically a mouthpiece having telescoping pivoted sections furnished with 30 means for maintaining the sections in alignment, independent of their respective adjustments, to preserve at all times a continuous channel throughout the mouthpiece.

A further object of the invention is the association of a suitable brush, preferably of a 35 rotary type, with a mouthpiece, and improved means for connecting together and adjusting the relative positions of the mouthpiece and broom; this combination, in a practical embodiment thereof, including a brush 40 of a flexible nature adapted to adjust itself in consonance with the adjustment of the flexible mouthpiece to which I have hereinabove alluded.

The invention further embraces a construction wherein a mouthpiece is employed 45 in conjunction with an air lifting and conveying means, and with a brush adapted to throw the refuse material from the street surface into the influence of the air passing 50 into the mouthpiece, a baffle or deflecting means being carried by the mouthpiece to prevent the throwing of the refuse therebeyond.

The invention still further contemplates 55 the provision of improved counterbalancing

means for the mouthpiece and brush enabling the latter to rise and fall to follow the contour of the road surface; and, preferably, such counterbalancing means co-operatively related to mechanism for raising the mouthpiece and broom out of operative association with the surface over which the machine travels.

The foregoing and many other features of detail and combinations of parts constituting refinements of the present invention will be more readily understood from the accompanying drawings forming part hereof, when considered in connection with the specific description thereof hereinafter contained, and wherein the preferred embodiment of the invention is disclosed.

In the drawings,

Figure 1 is a side elevation of a portion of a street sweeper possessing the improvements desired to be protected herein,

Fig. 2 is an enlarged elevation of the connecting and adjusting means between the mouthpiece and broom,

Fig. 3 is a rear elevation of the flexible mouthpiece,

Fig. 4 is a longitudinal sectional view of the sectional brush,

Fig. 5 is a partial end view,

Fig. 6 is a front view of the counterbalancing means and associated parts, parts being shown in section,

Fig. 7 is a top plan view thereof,

Fig. 8 is a detail longitudinal section on the line 8—8 of Fig. 7 showing one of the counterbalancing weights and connections therefor,

Fig. 9 is a vertical longitudinal sectional view, and

Fig. 10 is a detail sectional view. 95

Referring more specifically to the drawings, wherein like reference characters refer to the corresponding parts in the several views, A represents a rotary brush designed to loosen the refuse from the street or road surface and throw it into the range of influence of a volume of air passing into the mouth of a conduit B, the latter being coupled through branches b b' and flexible tubular connections C, C' to the opposite sections D, D' constituting the mouthpiece.

The sections of the mouthpiece are tapered at their upper portions, as shown, to merge into the cylindrical coupling members C, C', while at their lower ends they are elongated 110

and combined to constitute a substantially oblong inlet opening E, the adjoining inner sections of the mouthpiece overlapping, as at F, and being pivotally united by a bolt G to 5 permit the sections to move relative to each other around the axis of said bolt, in keeping with the surface of the ground, while at all times maintaining the continuity of the inlet opening of the mouthpiece. The sections of 10 the mouthpiece are maintained in alinement and reinforced against lateral strains by means of a bar H secured at h to the section D' and working through a bracket h' on the section D, the bar being formed on an arc 15 concentric to the pivot bolt G.

At the upper surface of the mouthpiece, I arrange a correspondingly sectional deflector I provided with adjustable mountings i for determining the projection of the sections 20 with reference to the mouthpiece, these sections, or baffles, serving to prevent the throwing of the dirt upwardly beyond the opening of the mouthpiece by the brush. The adjustable mountings i enable the projecting 25 and retracting of the deflector, as indicated by dotted lines, Fig. 2, the sections being locked in place by bolts i' and nuts i'', passing through slots i''' in the brackets at the ends of the mouthpiece, (Figs. 2 and 3). 30 It is observed that the opening E in the mouthpiece inclines upwardly and rearwardly owing to the curvature of the mouthpiece throughout the body portion thereof, and that said opening faces rearwardly of 35 the direction of travel of the vehicle, the bottom of the mouthpiece being provided with a trailing flexible contact strip J adapted to wipe along over the surface of the ground to prevent the dirt being thrown beneath the mouthpiece, following in that 40 respect the general purposes of the adjustable deflector I at the top of the mouthpiece.

In advance of the mouthpiece I may, should occasion require, secure sectional 45 scrapers in the nature of brushes K,—one carried by each section of the mouthpiece,—designed to loosen the matter to be collected from the street, prior to the lifting of such matter by the brush A to be thrown by such 50 brush toward the inlet opening of the conduit mouth.

The brush A is mounted to rotate upon an axle L mounted at its opposite ends in bearings M, swiveled upon the swinging supporting bars O, the lower ends of the bars 55 passing through sleeves n integral with the bearings and headed, as at N, to prevent withdrawal thereof. The opposite ends of the arms are pivoted upon a supporting 60 shaft P. This mounting of the brush upon the arms O permits the same to rise and fall following its contact with the road surface, and to insure the same movement of the mouthpiece so as to maintain the fixed operative 65 relation of the mouthpiece and brush

at all times, the brush and mouthpiece are rigidly and adjustably united as follows, to wit: Q are rearwardly extending bars securely fastened to the ends of the mouthpiece, the free ends of said bars being 70 formed into T-heads having vertical slots q therein enabling the relative adjustment of the broom and mouthpiece in a vertical direction; these T-heads lying adjacent to similar projecting portions R on the bearing members M provided with horizontal slots r permitting relative horizontal adjustment of the mouthpiece and brush, bolts S passing through the slots q and r at the intersection thereof and binding the parts in 80 the desired fixed adjustable position.

To relieve the bearings of lateral strains, the side bars or arms O are slotted as at o for the accommodation of depending guide arms T fixedly secured to the frame of the 85 machine in position to have the arms O work up and down freely thereover, as the brush and mouthpiece rise and fall, it being understood that the flexible connections C, C' for the mouthpiece,—which is conveniently 90 formed of strong metal,—permit the mouthpiece to move vertically while maintaining its operative association with the conduit.

To enable the broom to adjust itself vertically in keeping with the surface of the 95 ground, the axle L thereof is formed in sections (shown as of equal length), the inner end of one of the sections being formed into a socket l and the inner end of the other section being formed into a rounded knob 100 l' affording a universal union at the center of the brush A, the latter being correspondingly formed of sections, alining with the sections of the mouthpiece, and having the bristles a at the juncture of the sections converging outwardly to meet at the center of the brush and close over and around the space required for the coupling members l, l' just defined.

U represents the exhaust fan, to the eye 110 of which the conduit B is fastened, and u is a fragmentary portion of a conduit leading from the discharge portion of this fan to the point of deposit desired. The fan is driven from any suitable motor driving the 115 shaft V, and the brush A is driven from the same shaft through the medium of the chain connections v transmitting motion to the sprockets v' on the shaft P and from thence through a chain v'' to the sprockets v''' on the brush shaft or axle L, Fig. 1, it being understood that the driving connections for the brush are duplicated at the opposite end of the brush on the other side of the machine. By this means, it will be seen that 120 the driving power for the brush may always exert its operating energy upon the brush independently of the vertical adjustment of the latter.

To facilitate the rise and fall of the com- 130

bined brush and mouthpiece, it is desirable that counterbalancing means therefor be provided, and it is also expedient that means be provided additionally to said counterbalancing means, for elevating the brush and mouthpiece to a position away from operative association with the ground when the machine is not in service. To these ends the following instrumentalities are furnished:

- 10 W, W' are a pair of bars disposed transversely of the machine, the outer ends of the bars being twisted and offset so as to be bolted as at w to the opposite ends of the mouthpiece, this fastening being a rigid one.
- 15 The opposite, or meeting ends of the bars are formed so that they have an interfitting, or overlapping, relation, that is, the bar W is continuously straight, whereas the bar W' is forked or bifurcated as at w'; a roller w²
- 20 passing through slots w³, w⁴ in the overlapped ends of the bars to permit said ends to play over each other upon the roller acting as a pivot disposed in the vertical plane of the pivot G of the mouthpiece sections.
- 25 To the opposite ends of the bolt or other axle w⁵ of the roller, to which I have just referred, I secure a clevis w⁶, from which is suspended a link X, the latter being split at its upper end x to receive the closed lower
- 30 end of the clevis, and carrying a roller x' rocking in the latter. The lower end of the link X is connected to the pivot G of the mouthpiece sections, as illustrated (Fig. 5).

Also, passing through the split upper end 35 of the link X is the end of an arm Y, the same being slotted as at y to receive a roller y' mounted upon a pin y² supported for adjustment in any of the apertures y³ of the link X. The arm Y is carried rearwardly 40 for some distance and in a horizontal direction from the link, and then bends downwardly and terminates in a bearing sleeve y⁴ surrounding the cupped or socketed end 7 of the shaft section L, all of the connections 45 now being described being in the plane of the pivot of the mouthpiece sections, so as to permit the broom sections and mouthpiece sections to rise and fall together, and the rollers to which I have alluded being provided for antifriction purposes, as will be 50 obvious. From the bearings y⁴ an integral arm Y' extends forwardly to pivot upon the shaft P.

Intermediate the ends of the bars W and 55 W', I provide eyes z to which the lower ends of chains z' are attached, the upper ends of the chains being secured to levers z², pivoted to the frame of the machine, as at z³, the outer or free ends of the levers carrying 60 counterbalancing weights Z.

The weights are designed to counterbalance the combined weights of the broom and mouthpiece, and through the flexible connections hereinabove set forth the broom and 65 mouthpiece are normally free,—when the

counterbalancing weights are in action,—to rise and fall to automatically accommodate themselves to irregularities in the ground surface.

At times, as when the machine is being 70 moved from place to place, it is expedient that the brush and mouthpiece be raised a substantial distance from the ground, and be held in inoperative position, this being accomplished by means of a hand or foot 75 lever 2 rigidly connected to a transverse shaft 3 rotatably mounted in bearings 4 on the framework of the machine, and said shaft having projecting arms 5 rigidly connected thereto,—one formed integrally with 80 the lever 2,—the arms having offset notched fingers 6 adapted to engage the under side of the weight levers z² at the ends thereof opposite to the weights Z, so that when the arms 5 are raised the weighted ends will 85 fall, and the brush and broom raised by engagement of the arms with the levers z², any suitable means as a ratchet and pawl being employed to lock the lever 2 in adjusted 90 positions. It will be observed that the pivoting of the weight levers z² at z³ is upon the shaft 3, and that the weight levers are arched at their middle portions z⁴ to pass over the cross beam z⁵ of the frame of the machine. 95

While I have herein disclosed one specific embodiment of the invention, it is to be understood that the invention is capable of embodiment in other forms and devices without departing from the spirit thereof, and as 100 may be in keeping with the hereto appended claims.

I claim:

1. In a street sweeping machine, the combination with a sectional broom, of a flexible 105 sectional mouthpiece associated with a conductor to carry off the refuse liberated by the broom, means for mounting the brush and broom to permit them to rise and fall relatively to the ground, and a common 110 counterbalancing means for the brush and mouthpiece comprising bars secured to the outer ends of the mouthpiece and flexibly connected together, connecting instrumentalities between said flexible connection and 115 the corresponding connection between the broom sections, and counterbalance weights associated with the bars, substantially as described.

2. In a street sweeping machine, the combination with a sectional broom, of a flexible 120 sectional mouthpiece associated with a conductor to carry off the refuse liberated by the broom, means for mounting the brush and broom to permit them to rise and fall 125 relatively to the ground, a common counterbalancing means for the brush and mouthpiece comprising bars secured to the outer ends of the mouthpiece and flexibly connected together, connecting instrumen- 130

- 5 talities between said flexible connection and the corresponding connection between the broom sections and counterbalance weights associated with the bars, and the connecting means between the flexible connection of the bars and the corresponding connection of the broom sections comprising an adjustable link coupling member, substantially as described. 70
- 10 3. In a street sweeping machine, the combination with a sectional broom, of a flexible sectional mouthpiece associated with a conductor to carry off the refuse liberated by the broom, means for mounting the brush and broom to permit them to rise and fall relatively to the ground, a common counterbalancing means for the brush and mouthpiece comprising bars secured to the outer ends of the mouthpiece and 75 15 flexibly connected together, connecting instrumentalities between said flexible connection and the corresponding connection between the broom sections and counterbalance weights associated with the bars, 20 25 and the connecting means between the flexible connection of the bars and the corresponding connection of the broom sections comprising an adjustable link coupling member, one end of said link coupling member being connected to the flexible connection between the sections of the mouthpiece. 30 35 4. In a street sweeper, the combination with a broom having sections movable with reference to each other and with reference to the street surface, of a mouth piece having portions similarly movable with reference to each other and with respect to the street surface, means for connecting the outer ends of the broom sections with the corresponding outer ends of the mouth piece whereby they may rise and fall together, 40 45 coupling means between the inner portions of the broom sections and the mouth piece, and counterbalancing means for the mouth piece and broom sections, substantially as described. 50 55 5. In a street sweeper, a conduit, and a mouthpiece for the conduit mounted to occupy a position in close proximity to the ground, said mouthpiece comprising a plurality of sections arranged in substantially longitudinal alinement and pivotally connected at their ends to adjust themselves in keeping with the irregularities of the surface of the ground and the ends of said sections overlapping each other to form substantially continuous front and rear walls of the mouth piece, in combination with rigid arms pivoted at one end to the frame of the machine and at the other end connected to and carrying the outer ends of the outermost sections. 80 85 90 95 100 105 110 115 120 125 130
6. In a street sweeper, a conduit, and a mouthpiece for the conduit mounted to occupy a position in close proximity to the ground, said mouthpiece comprising a plurality of sections arranged in substantially longitudinal alinement and pivotally connected at their ends to adjust themselves in keeping with the irregularities of the surface of the ground, in combination with a rotary brush mounted in rear of said mouth piece and formed of freely movable sections corresponding to the sections of the mouth piece, and connections between the brush and mouth piece sections, whereby they are elevated and lowered in consonance with each other. 7. In a street sweeper, a conduit, and a mouth piece for the conduit mounted to occupy a position in close proximity to the ground, said mouth piece comprising a plurality of sections arranged in substantially longitudinal alinement and pivotally connected at their ends to adjust themselves in keeping with the irregularities of the surface of the ground, in combination with a rotary brush mounted in rear of said mouth piece and formed of freely movable sections corresponding to the sections of the mouth piece, and connections between the brush and mouth piece sections, whereby they are elevated and lowered in consonance with each other. 8. In a street sweeper, a conduit, and a mouth piece for the conduit mounted to occupy a position in close proximity to the ground, said mouth piece comprising a plurality of sections arranged in substantially longitudinal alinement, and pivotally connected at their ends to adjust themselves in keeping with the irregularities of the surface of the ground, in combination with a rotary brush mounted in rear of said mouth piece and formed of freely movable sections corresponding to the sections of the mouth piece, and connections between the brush and mouth piece sections whereby they are elevated and lowered in consonance with each other, in combination with rigid pivoted arms carrying the mouth piece and brush and counterbalancing instrumentalities for the brush and mouth piece operatively associated with said rigid pivoted arms. 9. In a street sweeper, a conduit, and a mouth piece for the conduit mounted to occupy a position in close proximity to the ground, said mouth piece comprising a plurality of sections arranged in substantially longitudinal alinement and pivotally connected at their ends to adjust themselves in keeping with the irregularities of the surface of the ground, in combination with a rotary brush mounted in rear of said mouth piece and formed of freely movable sections corresponding to the sections of the mouth piece, and connection between the brush and mouth piece. 10. In a street sweeper, a conduit, and a mouthpiece for the conduit mounted to occupy a position in close proximity to the ground, said mouthpiece comprising a plurality of sections arranged in substantially longitudinal alinement and pivotally connected at their ends to adjust themselves in keeping with the irregularities of the surface of the ground and the ends of said sections overlapping each other to form substantially continuous front and rear walls of the mouth piece, in combination with rigid arms pivoted at one end to the frame of the machine and at the other end connected to and carrying the outer ends of the outermost sections.

the brush and mouth piece sections whereby they are elevated and lowered in consonance with each other, in combination with counterbalancing instrumentalities for the 5 brush and mouth piece, a part of said counterbalancing instrumentalities being connected substantially at the point of junction between the sections of the brush.

10. In a street sweeper, a conduit, a mouth piece therefor mounted for free movement with respect to the ground, a brush in rear of said mouth piece movable therewith, and means for both vertically and horizontally adjusting the positions of 15 the mouth piece and brush relative to each other and for holding them in rigid relation after adjustment.

11. In a street sweeper, a conduit, a mouth piece therefor self adjustable with reference 20 to the ground, a brush adjustable therewith, counterbalancing instrumentalities for said mouth piece and brush normally free to move therewith, and means for adjusting the positions of the mouth piece and brush relative 25 to each other and for holding them in rigid relation whereby the one cannot rise and fall without the other after adjustment.

12. In a street sweeper, a conduit, a mouth piece therefor composed of a plurality of 30 movably connected sections having their adjoining end walls cut away to provide a continuous inlet, and a rotary brush in rear of said mouth piece composed of a plurality of pivotally connected sections, the bristles of 35 the adjoining ends of the sections projecting toward each other to form a continuous brushing surface substantially co-extensive with said inlets of the mouth piece.

13. In a street sweeper, a conduit, a mouth 40 piece therefor, a brush in rear of said mouth piece, yieldable means for supporting the mouth piece and brush whereby they may automatically rise and fall, and adjustable connecting instrumentalities intermediate the 45 broom and mouth piece for relatively adjusting them laterally and vertically whereby the one is compelled to rise and fall simultaneously with the other to conform to irregularities in the surface of the ground 50 while maintaining their predetermined relation.

14. In a street sweeper, a conduit, a sectional mouth piece therefor, a rotary brush arranged to throw the material into said 55 mouth piece, a correspondingly sectional deflector at the top of the entrance to the mouth piece for preventing the escape of the brushed material beyond the mouth piece, and means for adjusting any of the sections 60 of the deflector independently of the other sections thereof.

15. In a street sweeper, a conduit, a mouth piece therefor having an approximately vertically disposed inlet opening, a brush 65 mounted outside of said opening for throw-

ing the material into said mouth piece, said brush comprising a plurality of sections flexibly connected together to rise and fall independently of each other in keeping with the irregularities of the ground, and means 70 connected at the point of juncture between the sections assisting in supporting the same.

16. In a street sweeper, a conduit, a mouth piece therefor, a brush for throwing the material into said mouth piece, supporting 75 means including a substantially free vertically swinging arm connected to said brush, and a rigid approximately vertically disposed guiding member depending from the frame of the machine engaging an aper- 80 tured portion of said arm for preventing lateral play of the arm.

17. In a street sweeper, a conduit, a mouth piece therefor, a brush for throwing the material into said mouth piece, supporting 85 means including a substantially free vertically swinging arm connected to said brush and mouth piece, a rigid approximately vertically disposed guiding member depending from the frame of the machine engaging an 90 apertured portion of said arm for preventing lateral play of the arm.

18. In a street sweeper, a conduit, a mouth piece therefor, a flexible sectional brush for throwing the material into said mouth piece, 95 substantially free vertically swinging arms, swivel connections between said arms and the ends of the outer sections of the brush, and a counterbalance connected to the coupling intermediate the sections of the brush. 100

19. In a street sweeper, a conduit, a mouth piece therefor, a flexible sectional brush for throwing the material into said mouth piece, spacing connections between the brush and mouth piece, substantially free vertically 105 swinging arms swiveled at the ends of the outer sections of the brush, and a counterbalance connected to the coupling intermediate the sections of the brush.

20. In a street sweeper, a conduit, a mouth piece therefor, a flexible sectional brush for throwing the material into said mouth piece, spacing connections between the brush and mouthpiece, whereby they will rise and fall to the same extent, substantially free vertically swinging arms swiveled at the ends of the outer sections of the brush, and counterbalancing means operatively associated with the swinging arms. 110

21. In a street sweeping machine, an exhaust fan, a conduit leading thereto, a narrow elongated mouth piece for said conduit disposed in proximity to the roadway and consisting of interfitting sections associated to form a continuous receiving opening and 115 pivotally connected together, whereby said elongated mouth piece may be deflected and caused to conform to the contour of the roadway. 120

22. In a street sweeper, its frame, guide 130

- arms pivotally supported at one end to the frame of the machine and adapted to swing in a vertical plane, a broom journaled at the opposite end of said guide arms, an exhaust 5 fan, a conduit leading from the broom to the fan, a mouth piece for said conduit supported by the guide arms, and means for the vertical adjustment of said mouth piece in relation to said guide arms.
- 10 23. In a street sweeper, its frame, guide arms pivotally supported at one end by the frame of the machine and adapted to swing in a vertical plane, a broom journaled at the opposite end of said guide arms, a fan, a 15 conduit leading from the broom to the fan, a mouth piece for said conduit supported by the guide arms, and means for the horizontal adjustment of the mouth piece in relation to the broom.
- 20 24. In a street sweeper, its frame, guide arms pivotally supported at one end by the frame of the machine and adapted to swing in a vertical plane, a broom journaled at the opposite end of said guide arms, an 25 exhaust fan, a conduit leading from the broom to the fan, a mouth piece for said conduit supported by the guide arms, means for the horizontal adjustment of the mouth piece in relation to the broom, and means 30 for the vertical adjustment of said mouth piece in relation to said guide arms.
- 35 25. In a street sweeper, a revolving broom, a suction device, a conduit leading to said suction device and opening approximately rearwardly whereby to face in the direction of the revolving broom, and a deflector at the top of the mouth of said conduit adapted to project from said mouth and prevent throwing of the material beyond the conduit.
- 40 26. In a street sweeping machine, a broom, a fan, a tubular mouthed conduit leading from a point near the broom to the fan, adjustable connections compelling the mouth of the conduit and the broom to move up and down together, a portion of the conduit being flexible to permit the mouth of the same and the broom to rise and fall in keeping with the irregularities of the 45 ground surface.
- 50 27. In a street sweeper, a broom, a fan, a conduit leading from the broom to the fan, a mouth piece for the conduit having a deflector adjacent its inlet opening, and 55 means enabling the adjustment of said deflector.
- 60 28. In a street sweeping machine, a brush or broom, a fan, a conduit leading from the brush or broom to the fan, pivotal supports for said conduit, flexible connections in said conduit intermediate its inlet and the fan, and means for automatically controlling the vertical movement of the conduit.
- 65 29. In a street sweeper, a cylindrical broom, a fan, a conduit leading from the broom to the fan, a mouth piece for the conduit, a counter balance, and connections between said counterbalance and the mouth piece and the broom whereby the vertical 70 movement of both the broom and the mouth piece are controlled by said counter balance.
30. In a street sweeper, guide arms, pivotally supported at one end upon the machine and adapted to swing in vertical 75 planes, a brush or broom, a sectional shaft for the broom, boxes or journals for said shaft, swiveled connections between said boxes or journals and the other end of said pivoted guide arms, which permit said 80 shafts to be deflected at angles to the plane of said guide arms.
31. In a street sweeping machine, a fan, a broom, a conduit leading from the broom to the fan, a mouth-piece for said conduit supported by guide arms, means enabling horizontal adjustment of the mouth-piece in 85 relation to the broom, and means enabling vertical adjustment of said mouth-piece in relation to the guide arms. 90
32. In a street sweeping machine, a cylindrical broom, a sectional shaft therefor, means for pneumatically removing dust and dirt from in front of the broom, a conduit for the dust and dirt, a sectional mouth 95 piece for the conduit, swiveled bearings for said shaft, connections intermediate the broom and the mouth piece which cause the broom and mouth piece to move in harmony, the arrangement being such that 100 the sectional broom and the sectional mouth piece automatically accommodate themselves to the contour of the road.
33. In a street sweeping machine, a frame, a pair of guide arms pivotally connected 105 at one end to the frame, boxes swiveled upon the opposite end of said guide arms, and a broom having a sectional broom shaft journaled in said boxes.
34. In a street sweeper, a tubular conduit, a corresponding mouth piece therefor having an approximately rearwardly disposed inlet opening, a suction device for said conduit, a rotary brush mounted outside of and opposite to said opening, for throwing 110 material into the mouth piece, and means connecting said brush and mouth piece together, said means being formed for adjusting the mouth piece and brush toward and from each other to enable the maintenance 115 of a normal relation between the two.
35. In a street sweeper, guide arms pivotally supported at one end upon the machine and free to swing in a vertical plane, a broom having a substantially continuous sweeping surface, a shaft therefor, said shaft being in flexibly connected sections whereby the brush is yieldable in keeping with the ground surface at a point intermediate the ends of the brush, boxes for 120 125 130

said shaft, and swiveled connections between said boxes and the other end of said pivotal guide arms which permit the sections of said shaft to be relatively deflect-
5 ed at angles to the plane of said guide arms.

36. In a street sweeper, a broom consisting of movably connected longitudinal sections, a conduit leading from the broom
10 having a mouth comprising movably associated sections united at their meeting por-

tions, connections between the broom and the mouth piece which permit them to be deflected in harmony with each other, and counterbalancing means for the broom and 15 mouth piece.

In testimony whereof I hereunto affix my signature in the presence of two witnesses.

BERNARD KERN.
